LOCOMOTIVE TENDER

Joseph J. Kress, Erie, Pa., assignor to Standard
Stoker Company, Incorporated, a corporation of
Delaware

Application March 8, 1938, Serial No. 194,545

4 Claims. (Cl. 105—234)

This invention relates to locomotive tenders which are equipped with a fuel conveyor of a locomotive stoker.

It is the principal object of this invention to so arrange the stoker conveyor in the locomotive tender that the drive mechanism for the conveyor is adequately protected from the water, and whereby repair of the drive mechanism may be conveniently carried out.

10 A further object of this invention is to provide a stoker conveyor having a drive mechanism housing which forms a more or less permanent part of the conveyor; such housing arranged to maintain the drive mechanism in operative relation 15 and adapted to be immersed in the water compartment of the tender.

It is also an object of this invention to so arrange the drive mechanism within said housing that assembly and disassembly of said drive mechanism may be carried on from a position in the tender fuel bin and in a manner whereby the drive mechanism housing is not disturbed from its position in the stoker conveyor.

It is also an object of this invention to provide 25 a new and improved gear drive having several gear trains housed within a suitable casing having an aperture, for removal of such gear trains, which opening is smaller than the space occupied by the gear trains.

30 These and other objects, together with their attendant advantages, will become apparent as the following description is read in connection with the accompanying drawings, in which:

Fig. 1 is a sectional view of the forward portion of the improved tender taken along the vertical medial plane of the said tender, portions of the invention being shown on the line 1—1 of Fig. 2;

Fig. 2 is a transverse sectional view taken on 40 the line 2—2 of Fig. 3;

Fig. 3 is a sectional view in plan taken along the line 3—3 of Fig. 4;

Fig. 4 is a view similar to Fig. 2 with a cover removed to show the interior of the drive mechanism housing;

Fig. 5 is a view similar to Fig. 2 showing a modification as viewed along the line 5—5 of Fig. 6; and

Fig. 6 is a transverse sectional view taken along 50 the line 6—6 of Fig. 5.

Referring now to the form of the invention illustrated in Figs. 1 to 4, inclusive, T represents the tender, having a tank 10 mounted above the frame 11. The tank 10 includes a fuel compartment or bin 12 and a water compartment 13. A

horizontally disposed plate 14, spaced above the frame 11, forms the bottom of the fuel bin 12.

Fuel in the bin 12 is received by a conveyor C, extending into the water compartment 13 in a manner to occupy but little of the space available for the water supply. The conveyor C includes a trough conduit 15, approximately V-shaped in transverse cross section. At its forward end, the trough conduit 15 is provided with a vertical plate 16, forming a water tight closure 10 at the front of the tender tank. The bottom plate 14 is provided with a longitudinally extending central aperture 17 through which the conveyor C is adapted to pass downwardly from the fuel bin 12 into the water compartment 13. The 15 upper sides of the trough conduit 15 are flanged outwardly as at 18 and overlap the bottom plate 14 along each side of the aperture 17. The trough conduit 15 is secured by welding 18a to the bottom plate 14 in water-tight fashion. 20

To the inner side of the vertical plate 16 a crusher 19 is secured for cooperating with the conveyor screw 20 to reduce oversize lumps of fuel as the conveyor screw urges the fuel forwardly. The fuel enters the trough conduit 15 through its upwardly opened mouth 21; slideable plates 22 are mounted to form an opening 23 at various points along the trough conduit 15. To the forward side of the vertical plate 16, a spherical shell 24 is secured forming one element of a ball and socket joint between the conveyor C and a conveyor leading forwardly to the locomotive (not shown).

The conveyor screw 20 is substantially coextensive in length with the trough conduit 15 and 35 is provided at its rearward end with a polygonal socket 25. This socket 25 receives a complementary polygonal outward portion 26 of a shaft 27 operated by drive gearing D. The drive gearing D includes appropriate shafts and gears 40 which are housed within and maintained in operative relation in a gear case 28. On its forward side, the gear case 28 is provided with a wall 29 whereby it is rigidly attached to the rear end of the trough conduit 15. The joint between 45 the gear case wall 29 and the trough conduit is made water-tight by welding a bent angle iron 30 in position. A portion of the gear case 28 extends below the trough conduit 15. That portion of the wall 29 which is within the confines of the trough conduit 15 is apertured at 31 in order to provide access into the interior of the gear case 28. The rear wall 32 of the gear case is imperforate.

50 A cover 33 is secured by bolts 34 to the forward 55

wall 29 and serves as a closure for the aperture 31. In approximate axial alignment with the conveyor screw 20, the cover 33 is provided with a bearing 35 which receives the front journal 36 of the shaft 27. The rear journal 37 of this shaft is received in a bearing 38 formed in the imperforate rear wall 32 of the gear case 28. The shaft 27 is splined at 39 and carries thereat a gear 40, the lower portion of which extends into the gear case 28 below the 10 level of the trough conduit 15.

An intermediate shaft 41 is disposed at one side of the shaft 27 and it is provided with a front journal 42 received in a bearing 43 of the cover 43 of the cover 33 and a rear journal 44 carried in 15 the gear case rear wall 32. Between its journals 42, 44, the intermediate shaft 41 has formed thereon a pinion 45 with which the gear 40 is meshed. The teeth of the pinion 45 are of sufficient length to engage internal teeth 46 of a gear 20 46 of a gear 47 which is mounted on the intermediate shaft 41 immediately rearward of the gear 40. The gear 47 meshes with a pinion 48 formed on the primary shaft 49 arranged with its axis at one side of the trough conduit 15. The 25 front and rear journals 50, 51 of the primary shaft 49 are carried in the respective bearings 52, 53 formed with the gear case 28.

The forward end of the primary shaft 49 is connected by welding 54 to a shaft 55 leading forwardly to the front of the tender. A tube 56 surrounds the shaft 55 and is welded at its opposite ends of the gear case 28 and the vertical plate 16 at the front of the trough conduit 15. Adjacent the rear end of the trough conduit 15, the tube 56 opens into the trough conduit. A removable cover plate 57 covers the opening 58 between the tube 56 and the trough conduit 15.

Whenever it is necessary or desirable to have access to the interior of the gear case 28, the 40 sliding plates 22 are moved forwardly, conveyor screw 20 and the drive shaft 27 are disconnected and the gear case cover 33 is removed, as shown in Fig. 4. Since the gear 40 is splined on the shaft 27, the latter may be readily drawn forwardly. Since the lower portion of gear 40 is 45 below the level of the trough conduit 15, it is necessary to rotate the gear 40 upwardly about its pinion 45 to the position indicated by dot and dash lines in Fig. 4. The gear case 28 is purposely provided with a space 60 into which the 50 gear 40 may be rotated upwardly. From this position in space 60, the gear 40 may be drawn forwardly.

The intermediate shaft 41 may be drawn forwardly when the cover 33 is removed because the elongated pinion 45 provides a spline driving connection with the intermediate gear 47. With the intermediate shaft 41 removed, the gear 47 may be easily withdrawn from the gear case 28 by first moving it into the space 60. In order to permit removal of the primary shaft 49 through the tube 56, the outside diameter of pinion 48 is no greater than that of the front journal 50. Upon removal of the primary shaft 49, the cover plate 57 may be removed to provide access to bushings 52a, 53a of the bearings 52, 53, respectively. A tool may be inserted through the opening 58 for removing the bushings 52a, 53a.

In the modification shown in Figs. 5 and 6, the 70 gears 40a and 47a are keyed to their respective shafts 27a and 41a. Consequently, it is not convenient to remove the shafts 27a, 41a alone. Therefore, the gear 40a is disposed to the rear of the wall 29a a distance at least equal to the

depth of engagement of the rear journal 37a of shaft 27a with the rear bearing 38a formed in the imperforate rear wall 32a of the gear case 28a. Upon removal of the gear case cover 33a, the shaft 27a and gear 40a are drawn forwardly until the rear journal 37a is clear of the bearing 38a, then this assembly is moved upwardly in the space 60a and withdrawn from the gear case 28a. In order to similarly remove the intermediate shaft 41a and its gear 47a as a unit, the primary shaft 49a must first be drawn into the tube 56a. In all other respects this form of the invention is similar to the form illustrated in Figs. 1 to 4, inclusive.

Since the aperture is some distance above the bottom of the gear case, a lubricant reservoir below this aperture is formed. Thus, it may not be essential to drain off the lubricant before removing the cover over said aperture.

To those familiar with the art, it will be recognized that the drive gearing D in each form may be readily removed from and installed in operative position in the gear case from a position within the fuel bin. This will be found to be very convenient and results in the saving of 20 valuable water space which is otherwise occupied by drive arrangements of past practise.

I claim:

1. In a locomotive tender having a floor and a fuel compartment above said floor, a stoker conveyor positioned below the level of said floor, said stoker conveyor including a trough conduit and a conveyor screw rotatably mounted in said trough conduit, and drive mechanism for operating said conveyor screw from its rearward end, 30 said drive mechanism including a shaft operatively connected with and extending rearwardly from said conveyor screw beyond the end of said trough conduit, a gear mounted on said shaft, said gear extending below the bottom of said 40 trough conduit, a gear case housing said gear, said gear case on its forward side having a wall apertured above the level of the bottom of said trough conduit, the vertical extent of said aperture being at least as great as the diameter of 45 said gear, a detachable cover for said aperture, said gear case being formed to provide a space therein above the uppermost portion of said gear having a vertical extent at least as great as the distance said gear extends below the bottom of 50 said trough conduit, said gear being movable into such space upon withdrawal of said shaft for removal of said gear through said aperture from a position in said fuel compartment.

2. In a locomotive tender having a floor and a fuel compartment, said floor being provided with an aperture, a stoker conveyor positioned below the level of said floor, said stoker conveyor including a trough conduit opening upwardly into said fuel compartment through the aperture in said floor, a conveyor screw rotatably mounted in said trough conduit, drive mechanism for operating said conveyor screw from its rearward end, and a casing housing said drive mechanism, 60 said casing and drive mechanism extending below the level of said trough conduit, said casing extending upwardly through the aperture in said floor and on its forward side having a wall apertured above the level of the bottom of said trough conduit, said casing being formed to provide a space therein above said drive mechanism when said drive mechanism is in its operative relation with the conveyor screw, said drive mechanism being movable into such space for removal 65 70 75

through said aperture from a position in said fuel compartment.

3. In a locomotive tender having a floor and a fuel compartment, said floor being provided with an aperture, a stoker conveyor positioned below the level of said floor, said stoker conveyor including a trough conduit opening upwardly into said fuel compartment through the aperture in said floor, a conveyor screw rotatably mounted 10 in said trough conduit, drive mechanism for operating said conveyor screw from its rearward end, said drive mechanism including gearing extending below the level of said trough conduit, a gear case housing said gearing, said gear case 15 extending upwardly through the aperture in said floor and on its forward side having a wall apertured above the level of the bottom of said trough conduit, said gear case being formed to provide a space therein above said gearing when said 20 gearing is in its operative relation with the conveyor screw, said gearing being movable into such space for removal through said aperture from a position in said fuel compartment.

4. Conveying means including a trough con-

duit, a conveyor screw rotatably mounted in said trough conduit, and drive mechanism for operating said conveyor screw from its rearward end, said drive mechanism including a shaft operatively connected with and extending rearwardly from said conveyor screw beyond the end of said trough conduit, a gear mounted on said shaft, said gear extending below the bottom of said trough conduit, a gear case housing said gear, said gear case on its forward side having a 10 wall apertured above the level of the bottom of said trough conduit, the vertical extent of said aperture being at least as great as the diameter of said gear, a detachable cover for said aperture, said gear case being formed to provide a space 15 therein above the uppermost portion of said gear having a vertical extent at least as great as the distance said gear extends below the bottom of said trough conduit, said gear being movable into such space upon withdrawal of said shaft for 20 removal of said gear through said aperture into said trough conduit.

JOSEPH J. KRESS.

CERTIFICATE OF CORRECTION.

October 22, 1940.

Patent No. 2,219,073.

JOSEPH J. KRESS.

It is hereby certified that error appears in the printed specification of the above numbered patent requiring correction as follows: Page 1, second column, line 50, for "within" read --within--; page 2, first column, lines 13 and 14, strike out the words "of the cover 43"; lines 19 and 20, strike out "of a gear 46"; and that the said Letters Patent should be read with this correction therein that the same may conform to the record of the case in the Patent Office.

Signed and sealed this 14th day of January, A. D. 1941.

(Seal)

Henry Van Arsdale,
Acting Commissioner of Patents.
